UNITED STATES PATENT OFFICE.

ROY H. SMITH, OF CLEVELAND, OHIO.

COTTER-PIN MACHINE.

1,188,689.

Specification of Letters Patent. Patented June 27, 1916.

Application filed August 18, 1913. Serial No. 785,198.

To all whom it may concern:

Be it known that I, ROY H. SMITH, a citizen of the United States, residing at Cleveland, in the county of Cuyahoga and State 5 of Ohio, have invented a certain new and useful Improvement in Cotter-Pin Machines, of which the following is a full, clear, and exact description.

This invention relates to metal working 10 machines, and especially to cotter-pin machines, and to a method of forming cotter pins.

The main object of the invention is to provide a cotter pin machine which turns 15 out or manufactures automatically cotter pins more rapidly and at a less cost than is possible with the most improved machines in use at the present time.

The above object is attained by several 20 radically new features of construction and operation, chief of which is an arrangement by which I am enabled to do away with the necessity of utilizing previously drawn special half round wire stock, and 25 which receives ordinary round stock, and at the same time that it feeds the stock to the cutter and cotter forming dies, rolls or draws the same into half round stock, the feeding and drawing action being carried on at just the proper rate to permit 30 the cutting off tools to supply to the cutter forming dies lengths or sections of stock to form cotters of predetermined lengths which can be varied as desired. This is 35 an extremely important feature or improvement, for the reason that heretofore stock supplied or fed to a cotter pin machine had to be previously rolled or drawn to the half round shape, and the elimination of 40 the necessity for the previously formed special stock, or of the extra rolling operation, reduces very materially the cost of the finished product.

Another important part of my invention 45 resides in the mechanism for bending or doubling the cut-off stock sections downwardly between the dies, said mechanism being so designed or constructed as to admit of more rapid operation than heretofore, permitting especially a continuous feed of the stock, instead of an intermittent feed which has been utilized and in fact required in prior machines of this character.

The above and other features constitute 50 my invention which may be briefly summarized as consisting in certain novel de-

tails of construction and combinations and arrangements of parts which will be described in the specification and set forth in the appended claims.

In the accompanying sheets of drawings, 60 wherein I have shown the preferred construction of the main parts in the important particulars of the same, Figure 1 is a side view of the machine; Fig. 2 is a 65 side view looking toward the right of Fig. 1, parts being in section; Fig. 3 is an enlarged view, partly in section, and partly in side elevation showing the dies and the mechanism for bending the stock sections 70 downwardly between the same; Fig. 4 is an enlarged sectional view with parts in elevation showing the cut-off mechanism; Fig. 5 is a slightly enlarged view partly 75 in section, showing principally the cut-off mechanism, and the cotter finishing mechanism, including the dies and die carriers; Fig. 6 is a detail side view looking toward the left of Fig. 1, showing principally the operating means for the stock bending 80 mechanism; Fig. 7 is a detail sectional view showing the locking means for two of the speed changing shiftable gears.

The machine includes a frame 10, in the lower portion of which is journaled a main 85 drive shaft 11, which is provided at one end with a driving pulley 11^a. Splined to this shaft is a gear 12, which meshes with a gear 13 supported by a frame 14 which with the gear 12 is adjustable lengthwise 90 of the shaft 11. The gear 13 is adapted to engage and drive any one of a series of gears 15 of graduated sizes, all fixed to a shaft 16 supported by the frame above the shaft 11 and parallel thereto. The series 95 of graduated gears 15 enable the rate of feed of the stock to be varied to adapt the machine for various lengths of cotters. The frame 14 carries a spring pressed locking pin 14^a which cooperates with a segment 14^b having openings in which the pin may be inserted, and which are properly positioned to hold the frame and gears in any adjusted position.

The gears above described and others to be referred to are utilized in driving two cooperating stock feeding and drawing rolls 17 and 18, which feed the stock to the cutter and dies, and in the preferred construction are utilized to change or draw out ordinary round stock or wire to the half round shape which is required in the manufacture of

cotter pins. It will be observed that the lower roll is provided with a half round peripheral groove 17 while the upper roll is plain or cylindrical. These two rolls are secured respectively to the ends of two roll shafts 19 and 20, the former of which is journaled in the upper part of the frame and has fixed to it a large gear 21 which meshes with and is driven by the smallest 10 of the series of gears 15. Power is transmitted from the shaft 19 to the shaft 20 through the medium of two gears of equal size 22 and 23, secured respectively to the two shafts.

15 It will be observed that the upper shaft is journaled in a hollow body 24 which at its end remote from the rolls is pivoted to the part of the main frame which incloses and supports the lower roll shaft 19, and 20 which at its forward end adjacent the roll 18 is formed to fit closely between the parallel walls of a yoke 25 at the top of which is an adjustable screw 26 which bears on the top of the shaft carrying member 24 to 25 hold the two rolls firmly together, or to permit the clearance between the same to be varied to suit requirements. It will be observed that these parts just described are heavily designed with large bearings, etc., 30 in order that they may stand the great stresses and transmit heavy power required in drawing the stock to the half round shape.

In line with the rolls 17 and 18 is a cutter which cuts the stock into sections of the desired length. This cutter consists in this case of two co-operating rolls 28 and 29 carried by a block 30 secured in a slideway 31 of the frame by bolts 32 in such a manner 40 that the block and cutter rolls may be adjusted toward or away from the feed and drawing rolls 17 and 18. The stock is fed through peripheral grooves 28^a and 29^a in the cutter rolls, the groove 29^a in the upper 45 roll being shallow and having a flat base, while the groove 28^a of the lower roll is substantially half round and is provided at one point with a cutting tooth or projection 28^b which cuts the stock into the required 50 lengths, one section being thus cut off at each revolution of the two rolls.

The cutter roll 28 drives the roll 29 through two meshing gears 33 and 34, with 55 which the rolls are respectively provided, and the lower roll is driven from a shaft 35 which is journaled in the frame near the bottom thereof and is driven from the main shaft 11 through bevel gearing 36. The driving means between the lower shaft 35 60 and the cutter roll 28 consists of three shaft sections 37 connected by universal joints, a set of bevel gears 38 between the upper shaft section and the shaft on which the roll 28 is mounted, and another set of bevel gears 39 between the lower shaft section

and the driving shaft 35. It is important that the peripheral speed of the cutter rolls be not less than the linear speed of the stock after it passes through the feed and drawing rolls.

As the stock passes through the cutter rolls, it passes through a half round groove in the upper ends of a pair of finishing or forming dies 40 and 41, and when the stock is severed by the cutter, the dies should be 70 midway between the ends of the cutoff section, or the ends of the latter should extend equally on opposite sides of the dies. The location of the cutters will be such as to accomplish this result.

The two dies are removably held by pivoted holding or locking members 42, in the upper ends of a pair of rock arms 43 and 44 journaled in a bearing block 45. These rock arms are swung back and forth to close and open the dies by a plunger 46, the upper end of which is connected by toggle arms 47, to the lower ends of the rock arms. This plunger is lowered by gravity, or by other suitable means, if desired, to 85 open the dies, and is positively elevated to close the dies by a cam 48, on shaft 35, (see Fig. 2), which cam engages a roller on the lower end of the plunger.

As before stated, an important part of my invention resides in the mechanism for bending the wire stock or stock sections downwardly between the dies, and this part will now be described. Instead of utilizing a single bending device and one which is 90 moved back and forth by a reciprocating motion, I employ a plurality of rotating bending devices which are successively brought into action and are so arranged and actuated that while one is leaving the dies, and carrying with it a finished cotter, another is brought to position to bend the next wire section down into the dies, with the result that the cotters can be formed at a 95 much more rapid rate than heretofore.

By referring to Figs. 2 and 3, it will be seen that there is provided adjacent the dies, a rotating bending wheel 50 supported on a shaft 51, journaled in a bearing carried by a bracket 52 secured to the frame. The axis 100 of this shaft is parallel to the direction or line feed but is displaced laterally therefrom a little more than the radius of the wheel. This wheel carries a plurality of,—in this case, four—inwardly projecting short shafts 105 53, which are revolved by the wheel and are adapted to rotate slightly about their own axes. These shafts project inwardly slightly beyond the vertical central plane of the dies. Secured to the inner ends of these 110 shafts and projecting at right angles thereto are pins or fingers 54 which are located in the central vertical plane of the dies, and are adapted to bend the stock sections downwardly into the dies, as the wheel is rotated. 115

In Fig. 3, one of the pins 54 is carrying a finished cotter from between the dies, and another, or the one next to it, is about to bend the stock section which forms the next 5 cotter downwardly. It will be observed that the pin last referred to is horizontal and it will be apparent that it should remain horizontal or move in a path of parallelism with respect to the position referred to, until 10 the cotter is completed. In consequence, I provide a construction such that the angular position of the pin does not change from the time that the pin engages the stock section until the cotter is completed. This is accomplished 15 by means of a fixed cam 55 which is secured to the bearing for shaft 51 adjacent the bending wheel 50, and by providing on the outer ends of the shafts 53, cam like heels or shoulders 56, which engage the 20 face of the cam 55, so that the latter may control the positions or paths of the bending pins 54 as the bending shafts are rotated about the axis of the cam. It is necessary to control the position of each bending pin 25 only while it is moving through a portion of its cycle of movement. The substantially upright face or edge portion of the cam facing the die, as shown in Fig. 3, is the part which maintains the pin horizontal for the 30 period above stated.

The pin engages and bends the stock downwardly until the stock reaches the base of the finishing or shaping grooves of the dies, and thence the pin is held stationary 35 while the dies are closed, so that the eye of the cotter pin may be formed on the bending pin, and thence the movement of the bending pin is continued to carry the cotter from the dies. To accomplish this, the bending 40 wheel 50 is actuated intermittently by mechanism which includes a cam 58 having on its face an internal cam groove which is properly shaped to produce the desired results. This cam groove is engaged by a 45 roller on the arm 59 (see Figs. 2 and 6), whose lower end straddles the shaft 51, and whose upper end is pivotally connected to a link 60 loosely swung from the outer end portion of the shaft 51 upon which the bending 50 wheel 50 is mounted.

The pin 61 which connects the arm 59 to the link 60 carries a spring-pressed pawl 62, which co-operates with a ratchet wheel 63 fixed to the shaft 51 to turn the latter step 55 by step. The cam 58 is so shaped that during one complete revolution of the cam, the arm 59 is moved upwardly an extent to cause the pawl to move the ratchet wheel, shaft 51, and bending wheel 50 a sufficient 60 amount to cause one of the bending pins 54 to bend the stock section the full distance into the dies, and thence the pin 54 remains stationary while the dies are being closed onto the pin and stock section to form the 65 cotter and then the arm 59 is again given an-

other thrust upward to move the pin and with it the finished cotter from the dies, and to bring the next or following bending pin into a position to bend the next stock section into the dies. 70

A brief statement of the operation may now be given. The round wire stock is fed from a suitable roll or reel into the feed and drawing dies 17 and 18, where it is drawn into the half round shape and thence 75 is fed by these same rolls through an opening in the bracket 30 and through the cutter rolls which cut the stock into sections of the desired length. If it is desired to vary the length of the cotter, the gears 12 and 13 are shifted so that the latter will engage either a smaller or larger gear depending upon whether it is desired to increase or decrease the length of the cotter. Of course, the stock feeds out of the feeding 80 and drawing rolls at a faster rate than it feeds into the same, inasmuch as a unit section of the round stock has its length considerably increased by the action of the rolls. In consequence, to determine the rate 85 at which the rolls 17 and 18 must be revolved to feed the half round stock at the proper rate to produce cotters of the desired length, account must be taken of the amount that a unit section of the round 90 stock is increased in length by the rolling or drawing action, or the difference between the rate of feed of the half round stock over that of the round stock. When the rate of feed is changed to vary the length 95 of cotter, the position of the cutter rolls must be changed, not because the position of the cutter rolls affects at all the length of the cut-off sections, but in order that the cut-off sections will be properly positioned 100 with respect to the dies and the bending pins. Just as the section is cut off and lies over the upper ends of the dies, one of the bending pins engages the cut off section 105 midway between the dies and bends the 110 same downwardly into the latter in the manner shown in Fig. 5. Thence the dies are closed onto the stock section and bending pin, and the cotter is completed. While the dies are closing, the bending mechanism 115 is temporarily stationary as before stated, and thence as the dies are again opened, the finished cotter pin is removed from the dies and the next succeeding or following bending pin is brought to bending position 120 with reference to the dies. Meanwhile, the stock is being fed continuously through the rolls, and when the die is opened to permit the egress of the finished cotter, the stock is again fed over the same, the section is 125 severed by the cutter rolls, and the operation just described is repeated. This operation is carried on very rapidly and in fact much more rapidly than is possible with other types of machines which utilize inter- 130

mittent feeds for the stock and a reciprocating bending device which must take a complete cycle of movement, each time a cotter pin is formed. In my construction, four cotter pins are formed during the complete cycle of movement of each bending pin. This increased speed of operation reduces the cost of the finished product, but the feature of employing combined feed and drawing rolls, which allow a machine to use the round stock which is far less expensive than the special rolled half round stock, is perhaps the greatest factor in the reduction of the cost of the product of my improved machine.

While I have shown in the drawing, only the preferred construction, I do not desire to be confined to the exact details shown, for it is obvious that many of the parts may be varied considerably without affecting the results, and I therefore aim in my claims to cover all modifications which do not involve a departure from the spirit and scope of the invention as defined by the appended claims.

Having thus described my invention, what I claim is:

1. In a cotter pin machine, in combination, means for drawing round stock into half round stock, mechanism for cutting the half round stock into sections, means for bending the cut-off sections into cotter pins, and means for operating said parts in predetermined relationships to form cotters of predetermined length.

2. In a cotter pin machine, in combination, a pair of coöoperating drawing rolls for drawing round wire stock into half round stock, mechanism for cutting the stock into sections, mechanism for bending the sections into cotter pins, and means for operating said parts and mechanisms in predetermined relationships to form cotter pins of a given length.

3. In a cotter pin machine, in combination, means for drawing round wire stock in half round stock and for feeding the half round stock at a given rate, cutting mechanism for cutting the half round stock into sections of a predetermined length, and bending mechanism for bending the cut-off sections into cotter pins, and means for operating said parts.

4. In a cotter pin machine, in combination, combined feed and drawing rolls for drawing round wire stock into half round stock and for feeding the same through the machine at a predetermined rate, a cutter for cutting the half round stock into sections of predetermined length, dies for forming the cotter pins, means for bending the stock into the dies, and means for continuously driving the feed and drawing rolls.

5. In a cotter pin machine dies for form-

ing cotter pins from stock sections, a rotating device for bending stock sections into or between the dies, and means for closing the dies when the said device and the bent section of the stock is between the dies.

6. In a cotter pin machine, a pair of forming dies, an intermittently rotating device for moving and bending stock sections into or between the dies, and means for closing the dies on to said device and the bent stock section.

7. In a cotter pin machine, forming dies, a rotary member having a plurality of devices for moving and bending stock sections into the dies, and means for closing the dies when each of said devices and the bent stock section is between the dies.

8. In a cotter pin machine, a pair of forming dies, means for opening and closing the dies, and means for engaging sections of stock so as to bend the same into the dies, comprising a rotary member having a plurality of projecting pins, which successively bend stock sections into the dies when the latter are open.

9. In a cotter pin machine, a pair of dies, and mechanism for moving and bending stock sections into the dies comprising a rotating member having a plurality of stock moving and bending devices, each adapted to engage a stock section and to move and bend the same into the dies, and means for holding each of said devices against angular movement, while it is moving a stock section into the dies.

10. In a cotter pin machine, dies for forming cotter pins from stock sections and adapted to be opened and closed laterally, means for moving the stock sections downwardly into the dies and for bending the sections comprising a rotary member having a plurality of bending pins, and means for actuating said member to cause the pins to successively move stock sections into the dies.

11. In a cotter pin machine, dies for forming cotter pins from stock sections, means for moving the stock sections downwardly into the dies, and for bending the stock comprising a rotary member having a plurality of bending pins, means for actuating said member to cause the pins to successively move stock sections into the dies, and means for holding each of said bending pins in substantially horizontal position as it moves a stock section into the dies.

12. In a cotter pin machine, dies for forming cotter pins from stock sections, means for moving the stock sections downwardly into the dies, and for bending the sections, comprising a rotary member having a plurality of bending pins, and means for actuating said member, to cause the pins to successively move stock sections into the dies, means for holding each of said bending pins

in substantially horizontal position as it moves a stock section into the dies, and means for intermittently actuating said rotary member.

5 13. The method of forming cotter pins from round wire stock which consists in drawing the stock into half round stock and for feeding the same at a predetermined rate, cutting half round stock into sections 10 and thence forming the sections into cotter pins.

14. The method of forming cotter pins from round wire stock which consists in drawing the round stock into half round 15 stock and simultaneously feeding the half round stock at a predetermined rate, cutting the half round stock into sections at a predetermined rate with reference to the

rate of feed, and thence bending the sections into cotter pin form. 20

15. The method of forming cotter pins from round wire stock which consists in drawing round stock into half round stock and continuously feeding the same at a predetermined rate, cutting the half round 25 stock into sections of predetermined lengths and forming the cut-off section into cotter pin shape at a predetermined distance from the point at which the stock is cut into sections. 30

In testimony whereof, I hereunto affix my signature in the presence of two witnesses.

ROY H. SMITH.
